UNITED STATES PATENT OFFICE.

WILLIAM T. WALLACE, OF BOYLES, ALABAMA.

CAR-COUPLING.

1,171,817.

Specification of Letters Patent. Patented Feb. 15, 1916.

Application filed July 9, 1915. Serial No. 39,010.

To all whom it may concern:

Be it known that I, WILLIAM T. WALLACE, a citizen of the United States of America, residing at Boyles, in the county of Jefferson and State of Alabama, have invented 5 certain new and useful Improvements in Car-Couplings, of which the following is a specification.

My invention relates to improvements in 10 car couplers of the Janney type wherein a pivoted knuckle is provided with a tail-wing adapted to swing into and to be locked in a recess in the draw-head.

The object of my invention is to provide 15 the knuckle with a movable pivot by means of which it will shift when it assumes coupled position and move its tail-wing into engagement with fixed locking shoulders in the draw-head, and with this end in view 20 the knuckle is pivoted in the draw-head by a vertically movable shouldered pin which works in slots in the draw-head elongated axially thereof so that when the pin shoulders are disengaged from the slots, the 25 knuckle is left free to move bodily.

A further feature of my invention relates 30 to the novel means for unlocking and opening the knuckle and consists in lever mechanism so connected to an operating element 35 that its initial pull will set the pin to permit the outward or unlocking movement of the knuckle and the secondary movement will first force the knuckle outwardly until its tail-wing clears the locking shoulders 40 and will then bear against the tail-wing so as to swing the knuckle into open position.

My invention further consists in novel 45 means for setting the knuckle pin for uncoupling; the manner of designing the locking pin and the knuckle engaging shoulders in the draw-head to relieve the knuckle pin as much as possible of the buffing and pulling strains; and in the other novel details of construction and arrangement of parts 50 which in their preferred embodiment only are hereinafter more particularly described, reference being had to the accompanying drawings, in which:

Figures 1 and 2 are cross sectional views 55 taken on the line $x-x$ of Fig. 3, and showing the knuckle in its locked and unlocked position. Fig. 3 is a sectional view taken on the line $y-y$ of Fig. 1, showing the knuckle in elevation and in raised position. Fig. 4 is a similar view taken on the line $z-z$ of Fig. 2, showing the knuckle pin

in lowered or seated position. Fig. 5 is a perspective view of the draw-head with the knuckle removed. Fig. 6 is a detail of the lower end of the knuckle pin shown in section. Fig. 7 is a top plan view of the knuckle pin.

Similar reference numerals refer to similar parts throughout the drawings.

The draw-head 1 is provided on one side 65 with a jaw 2 and on the opposite side with spaced lugs or ears 3 having alining knuckle pin slots 4 that are elongated from front to rear of the draw-head. The draw-head is provided with an internal recess 5 having 70 a back wall 6 curved from its front face inwardly and rearwardly to a lock pocket 7. Where each ear 3 joins the head the latter is provided with a raised curved shoulder 8 terminating near the center line of the ear 75 in a laterally facing, locking shoulder 9. The lower shoulder 9 is raised above the lower ear and the upper shoulder 9 depends below the underface of the upper ear. The head is additionally provided with a 80 recess 10 which opens at its front end into the recess 6 in the head and is adapted to receive a sliding actuator 11 for moving the knuckle to unlock and open it. The knuckle 12 is provided with a tail-wing 13 85 of reduced thickness which is adapted to swing into the recess 6 and to have its rear end received in the lock pocket 7. The knuckle is pivotally mounted between the ears 3 by means of a vertical pin 14, which pin fits therein with a snug sliding fit near the junction of the knuckle and its tail-wing and passes through the slots 4 in the ears 3. This pin is provided at its upper end with an integral shoulder 15, which in cross section is adapted to fill out the slot 4 when seated therein. On the lower end of the pin 1 I provide a similar shoulder 15, but this lower shoulder is mounted upon a sleeve 16 which is fitted over the reduced tapered end 100 17 of the pin and is keyed thereto by the cotter pin 18.

On both the top and bottom face of the tail-wing I provide a raised shoulder 19 which surrounds the pin 14 except on the 105 side thereof facing the jaw 2 where the shoulders are interrupted to furnish the vertical inwardly facing locking shoulders 20 to the rear of the pin 14. The shoulder 19 on the bottom face of the knuckle is additionally cut away at 21 to form a recess that will receive and permit the knuckle to swing 110

about the lower shoulder 15 on the pin in the manner that will be observed by comparison of Figs. 1 and 2, which it will be noted show the bottom face of the knuckle. The curve of the wall 6 is such as to permit the tail-wing 13 to clear it in swinging about the pin when in the position shown in Fig. 1. The knuckle on its top and bottom is provided with a rearwardly facing curved shoulder 22 which is adapted to engage and bear against the rounded outer ends of the ears 3 so as to take the buffing strain off of the pin. The inwardly facing shoulders 20 on the top and bottom side of the tail-wing are adapted to abut against the outwardly facing lock shoulders 9 at the top and bottom of the draw-head when the knuckle is shifted rearwardly into locked position and this interlock will materially supplement the locking strength derived from the engagement of the tail-wing 13 in the lock pocket 7. This rearward motion of the knuckle is provided for by the rearward movement of the pin 14, when in raised position, in the slots 4 until the pin engages the rear walls thereof in which position the shoulders 15 are free to drop with the pin into and fill out the slots 4, thus locking the knuckle in its rearward position, as will be seen in Fig. 2. The recess 21 in the underface of the knuckle shoulder 19 permits the pin 14 to be raised thereinto until its shoulders 15 clear the slots 4, whereupon the knuckle is free to swing about the pin.

35 The operating mechanism for the actuator 11 and the knuckle pin 14 comprises any suitable member 23 which is adapted to be raised and lowered from the side of the car. To this member is pivoted at its center a link 24 having a link 25 suspended from its forward end and connected to a pin 26. This pin 26 extends through an arcuate slot 27 in the flattened head 28 of the pin 14 and through an angled lock set member 29 which is pivoted at its upper forward end to the side of head 28 by a pivot pin 30 and which has its depending rear end 31 offset so as to fit against the side of the pin 14. The upper slot 4 is cut out on one side 40 to permit this lock set to enter it as shown in Fig. 4. When the pin 14 is pulled upwardly the initial pull of pin 26 is on this lock set, the pin 27 being free to move to a limited extent in slot 27. This initial movement swings the lock set backwardly so that, when raised above the slot 4, it will engage and rest on a shoulder 32 at the rear end of the slot 4. A suitable reinforcing guard flange 33 surrounds the head of the pin on three sides and is cut away at 34 to receive the lock set. The rear end of the link 24 is connected by a chain 35 to a pin 36 in the forward end of a bell crank lever 37. This lever is pivoted between raised guard lugs 45 38 on top of the draw-head and has its lower

end passed downwardly through a slot 39 into the slot 10. The lower end of the lever is rounded and seated with a ball joint in a pocket 40 in the actuator 11 and the upward pull exerted on the lever will act to throw the actuator forwardly. It will be noted that the actuator is so disposed relatively to the axis of the knuckle that the initial pressure exerted by it against the tail-wing will act to move the knuckle bodily forwardly when the pin 14 has been lifted to permit this movement and it will be noted that this lifting of the pin will take place automatically in advance of any movement of the actuator. After the actuator has moved the knuckle to its outer position so that its tail-wing clears the lock pocket 7 and its shoulders 20 clear the lock shoulders 9, continued pressure against the curved face of the tail-wing serves to swing the knuckle about its axis and force it into uncoupled position.

In operation, assuming the knuckle open and the parts in the position shown in Figs. 1 and 3, the incoming head will swing the knuckle into coupling position and will then force it rearwardly into locked position when the pin shoulders 15 will drop into the slots 4 and hold the knuckle against movement from this position. To uncouple, the pin is raised by the lifting power applied to the member 23 and after completing the raising of the pin, the bell crank lever 37 is actuated and through the actuator 11 will unlock and open the knuckle. To set the knuckle for unlocking it is only necessary to lift it sufficiently to permit its lock set 31 to rest on the shoulder 32 on the draw-head.

What I claim as new and desire to secure by Letters Patent, is:—

1. In a car coupler, a draw-head having elongated knuckle pin slots, a knuckle pin vertically movable in said slots and having reduced portions which when opposite the walls of the slots permit the pin to move horizontally therein, a knuckle pivoted by said pin to the draw-head and having a tail-wing adapted to swing into the draw-head, a lock shoulder which said tail-wing is adapted to engage when the knuckle is shifted bodily toward the draw-head, and a combination pin lifting the knuckle shifting and opening mechanism, substantially as described.

2. In a car coupler, a draw-head having at one side lugs provided with elongated pin holes and having an integral recess, shoulders in the top and bottom of said recess facing to the near side of the draw-head, a knuckle mounted between the ears and having a vertical pin hole, a locking pivot pin for the knuckle which is mounted in said ear slots and is shouldered to fill said slots in one position and to have clearance in said

slots in another position, the lower shoulder on the pin being detachable, a tail-wing on the knuckle adapted to swing into said recess and, responsive to a body movement of the knuckle, to interlock with a wall of said recess, and having shoulders which in its locked position engage said shoulders on the draw-head and take the draft strain off the tail-wing, substantially as described.

10 3. A recessed draw-head having pin holes elongated from front to rear, a knuckle mounted to swing in the draw-head, a pivot pin for the knuckle vertically movable therein and provided with top and bottom shoulders adapted to be moved into and out of said elongated slots, said knuckle having shoulders adapted to bear against the draw-head to relieve said pin of buffing strains, and said head and knuckle having top and bottom internal shoulders disposed radially to the knuckle's axis and adapted to engage and interlock when the knuckle is shifted rearwardly in said draw-head, and mechanism for unlocking and swinging the knuckle outwardly, substantially as described.

15 4. In a car coupler, a draw-head having an internal recess, a knuckle seated in the

recess and having a vertically movable pivot pin, top and bottom shoulders on the pin, and a recess in the knuckle to receive and swing about one of the pin shoulders, slots in the draw-head elongated from front to rear and adapted to receive the pin and its shoulders, an actuator seated in the head, a slideway for said actuator in which it is movable from rear to front of the head to engage the rear face of the knuckle, a bell crank lever pivoted on the draw-head which is slotted to permit the lower end of the lever to engage and move said actuator, a flexible operating means connected to the upper ends of said pin and lever and adapted to exert its pull first on the pin to move the shoulder thereof out of said elongated slots, and then on the actuator to shift and swing the knuckle, and a shoulder in the head with which a portion of said knuckle interlocks when shifted with its pivot pin bodily to the rear in coupling.

In testimony whereof I affix my signature.

WILLIAM T. WALLACE.
